UNITED STATES PATENT OFFICE

FRANKLIN G. NEUBERTH, OF ANSONIA, CONNECTICUT, ASSIGNOR TO THE S. O. AND C. COMPANY, OF ANSONIA, CONNECTICUT, A CORPORATION OF CONNECTICUT

METHOD OF MANUFACTURING FASTENERS.

Original application filed October 5, 1923, Serial No. 666,862, and in Germany September 13, 1923.
Divided and this application filed December 30, 1925, Serial No. 78,414. Renewed July 24, 1929.

This invention relates to improvements in methods of manufacturing fasteners and is illustrated herein with reference to the manufacture of eyelets particularly adapted for blind and invisible eyeleting, of the type shown in my co-pending application for Letters Patent of the United States, Serial No. 666,862, filed October 5, 1923, of which the present application is a division.

10 The eyelet disclosed in said application for United States Letters Patent, Serial No. 666,862, has the portion of its barrel towards its entering end of a scalloped or polygonal formation, scored at the apexes of the polygon or of the scalloping, and has the extreme entering end of its barrel blunted to provide a plane end surface of substantial width. It is an object of the present invention to provide a satisfactory and economical method 15 for the manufacture of eyelets having any or all of these characteristics.

In accordance with the foregoing, important steps of the herein disclosed method are the simultaneous scoring and scalloping 20 of the eyelet barrel, and the blunting or upsetting of the entering end of the eyelet barrel while its interior is supported to prevent its collapse. In the fullest development of the method, the steps are performed in the 25 order just recited though it should be noted that their utility is not limited to their performance in this sequence. Moreover, while the invention is herein disclosed in connection with the manufacture of the eyelet of my 30 co-pending application, Serial No. 666,862, it should be understood that in various of its aspects its utility is not so limited.

With the above and other objects in view the invention will now be described in connection with the accompanying drawings and 35 pointed out in the claims.

In the drawings,

Fig. 1 is a perspective view on a much enlarged scale of an eyelet blank produced in accordance with any one of several well-known methods used in the manufacture of eyelets;

40 Figs. 2 and 3 are perspective and plan views, respectively, of the blank after it has been scalloped and scored in accordance with 45 the method of the present invention;

Figs. 4, 5 and 6 are a perspective view, a longitudinal section and a plan view, respectively, of the blank of Figs. 2 and 3 after its entering end has been blunted, these figures showing the eyelet in its completed form; 55

Fig. 7 is a longitudinal section of a die used in the scalloping and scoring of the eyelet barrel;

Fig. 8 is a section on the line VIII—VIII 60 of Fig. 7;

Fig. 9 is a perspective view of a punch which co-operates with the die of Fig. 7 to scallop and score the eyelet barrel;

Fig. 10 is a longitudinal section through the punch, die and eyelet during the scalloping and scoring operation, indicating also in dotted lines the position of the punch relatively to the die at the conclusion of that 65 operation;

Fig. 11 is a cross-section on the line 70 XI—XI of Fig. 10 with the eyelet omitted; and

Figs. 12 and 13 illustrate the upsetting and 75 blunting operation which is performed upon the entering end of the eyelet barrel. 75

The eyelet blank of Fig. 1 has substantially the form of the usual complete eyelet, being provided with a flange 100 and a barrel 102 tapering somewhat from its flange to its entering end. The extreme entering end 103 is quite sharp having an almost knife-like 80 edge as a result of the punching operation by which the entering end of the barrel is perforated in accordance with the usual practice in manufacturing eyelets. The blank thus formed is, in the illustrated exemplification 85 of the invention, introduced into a hollow die member 124 (Figs. 7, 8 and 11) formed with a series of ribs 126 separated by grooves 128, the ribs 126 tapering off at the entering end 90 of the die as shown at 130 in Fig. 7, thus forming an enlarged entrance 131. Conveniently, at its entering end the die is provided with a recess 132 adapted to receive the flange 95 of the eyelet blank to be operated upon. A punch 134, illustrated in Figs. 9, 10 and 11, is used in co-operation with die 124 to scallop and score the eyelets. This punch is itself scalloped, as clearly shown in Figs. 9 and 11, the successive scallops meeting and forming 100

cutting edges 136. The entering end of punch 134 is tapered to facilitate its introduction into the barrel of the eyelet blank which has previously been introduced into die 124, as shown in Fig. 10. Punch 134 is provided also with a shoulder 137 which co-operates with recess 132 of die 124 properly to limit the movement of punch 134 relatively to an eyelet blank operated upon.

- 10 The punch 134 enters the portion of the eyelet barrel adjacent to the eyelet flange freely and without obstruction but, as it passes toward the smaller entering end of the eyelet barrel, edges 136 of the punch score the interior of the barrel, cutting into the metal of the eyelet barrel a substantial distance and finally cutting all the way through the barrel at the entering end thereof, as shown at 106, Fig. 2. At the same time the barrel is scalloped, being forced into the space (indicated at 138, Fig. 11) between the punch 134 and die 124 and acquiring the formation shown in Figs. 2 and 3. Punch 134 is passed through die 124 approximately to the position indicated in dotted lines at 140 in Fig. 10, after which it is withdrawn leaving the eyelet blank in the condition shown in Figs. 2 and 3, with a thin, sharp edge 142 at its entering end. After this the eyelet blank is placed upon a 30 spindle 144 (Figs. 12 and 13) having a shoulder 146 arranged to support the flange 100 of the blank adjacent to the lacing hole and having a tapered portion 148, terminating in a cylindrical portion 150, arranged substantially to fill the open entering end of the eyelet barrel. Co-operating with spindle 144 is a die 152 having a hole therethrough of a size to be a good working fit on the cylindrical portion 150 of spindle 144. With the eyelet 35 blank supported upon spindle 144, as indicated in Fig. 12, die 152 and spindle 144 are given relative movement so as to force die 152 against the entering end of the barrel of the blank supported upon the cylindrical portion 150 of the spindle, upsetting (that is to say, shortening and thickening) as well as blunting the end of the eyelet barrel, as shown at 108, Fig. 13, and giving it a flat or plane end surface 104. Die member 152 is then 40 withdrawn and the eyelet, which now has the form shown in Figs. 4, 5 and 6, is removed from the spindle 144. After this the substantially completed eyelet may be subjected to any desired finishing operation.
- 45 The eyelet thus produced is well adapted to be used for blind or invisible eyeleting, as set forth in said application for Letters Patent, Serial No. 666,862.

By reducing the depth of grooves 128 in die 124 and by correspondingly reducing the size of punch 134, the depth of the scalloping of the eyelet may be reduced. Indeed this may be carried to such an extent that the entering end of the eyelet barrel will take the 50 form of a polygon each of whose sides is a

straight line instead of the curved line shown in Figs. 3 and 6. Such of the claims as include scalloping are intended to be construed as covering this as well as the more pronounced scalloping illustrated.

It should be understood that the word "score" is used in this specification in the sense in which it is commonly used in the eyelet art, that is to indicate a longitudinal cut extending a substantial distance into the metal of an eyelet barrel to facilitate the splitting of the eyelet barrel when it is clenched. A mere scratching or a bending of the metal, even a sharp bend, if without a substantial cutting of the metal, is not considered as scoring.

Having described the invention, what I claim as new and desire to secure by Letters Patent of the United States is:

1. That improvement in methods of manufacturing eyelets which comprises scoring and scalloping an eyelet barrel and thereafter upsetting the open entering end of the barrel to provide a blunted work-engaging end.

2. That improvement in methods of manufacturing eyelets which comprises simultaneously scoring and scalloping an eyelet barrel and thereafter upsetting the open entering end of the barrel to provide it with a blunted work-engaging end.

3. That improvement in methods of manufacturing eyelets which comprises supporting the flange and the interior surface of an eyelet barrel and thereby preventing its collapse and while the barrel is so held upsetting the open entering end thereof.

4. That improvement in methods of manufacturing eyelets which comprises supporting the flange and the interior surface of an eyelet barrel and thereby preventing its collapse but leaving the outer surface of the barrel unsupported and while the barrel is so held upsetting the open entering end thereof.

In testimony whereof I have signed my name to this specification.

FRANKLIN G. NEUBERTH.

CERTIFICATE OF CORRECTION.

Patent No. 1,756,257.

Granted April 29, 1930, to

FRANKLIN G. NEUBERTH.

It is hereby certified that the name of the assignee in the above numbered patent should have been written and printed "The S O and C Company", instead of "The S. O. and C. Company", as shown by the records of assignments in this office; and that the said Letters Patent should be read with this correction therein that the same may conform to the record of the case in the Patent Office.

Signed and sealed this 24th day of June, A. D. 1930.

(Seal)

M. J. Moore,
Acting Commissioner of Patents.
